UNITED STATES PATENT OFFICE.

DURAIN E. WELCH, OF UPPER SANDUSKY, OHIO.

DESIGN FOR A CONCRETE SHINGLE BLOCK FOR BUILDING WALLS.

Application filed March 5, 1928. Serial No. 25,672. Term of patent 3½ years.

To all whom it may concern:

Be it known that I, DURAIN E. WELCH, a citizen of the United States, residing at Upper Sandusky, in the county of Wyandot and State of Ohio, have invented a new, original, and ornamental Design for Concrete Shingle Block for Building Walls, of which the following is a specification, reference being had to the accompanying drawing, forming part thereof.

Figure 1 is a perspective view of the front face of a concrete shingle block for building walls, showing my new design, and

Figure 2 is a similar view showing the rear face of the same.

I claim:

The ornamental design for a concrete shingle block for building walls, as shown.

DURAIN E. WELCH.
